COMBINED SYRUP AND FRUIT DISPENSER

Bernard L. Rothbardt, Sherman Oaks, Calif., assignor to
Baskin-Robbins Ice Cream Company, Burbank, Calif.

Filed May 28, 1974, Ser. No. 474,049

Term of patent 14 years

Int. Cl. D15—08

U.S. Cl. D55—1 E

Fig. 2

Fig. 3

Fig. 4

Fig. 5

Fig. 6

Fig. 7

FIG. 1 is a perspective view of a combined syrup and fruit dispenser showing my new design.

FIG. 2 is a top-plan view thereof.

FIG. 3 is a front-elevation view thereof.

FIG. 4 is a bottom-plan view thereof.

FIG. 5 is a rear-elevation view thereof.

FIG. 6 is a left-side elevation view thereof.

FIG. 7 is a right-side elevation view thereof.

I claim:

The ornamental design for a combined syrup and fruit dispenser, substantially as shown and described.
